Corporation, Chicago, Ill., a corporation of Illinois

Application March 19, 1945, Serial No. 118,586

Term of patent 14 years

(Cl. D61—1)

To all whom it may concern:

Be it known that I, William C. De Vry, a citizen of the United States and a resident of Chicago, in the county of Cook and State of Illinois, have invented a new, original, and ornamental Design for a Portable Motion Picture Machine and Carrying Case Therefor, of which the following is a specification, reference being had to the accompanying drawing forming a part thereof, and in which:

Fig. 1 is a perspective view of a portable motion picture machine and carrying case therefor, showing the essential features of my design in full lines, the opposite side, end and bottom being substantially plain.

Fig. 2 is an end elevational view of the same.
I claim:

The ornamental design for a portable motion picture machine and carrying case therefor, as shown and described.

WILLIAM C. DE VRY.
